United States Patent Office

Des. 177,810
Patented May 29, 1956

177,810

ELASTIC SLIPPER OR SIMILAR ARTICLE

Preston E. Hiestand and Eugene V. Mills, Princeton, Wis.,
assignors to Handcraft Company, Inc., Princeton, Wis.,
a corporation of Wisconsin

Application June 20, 1955, Serial No. 36,586

Term of patent 14 years

(Cl. D7—7)

The single figure of the drawing is a view illustrating the ornamented article of footwear as it normally appears when not in use.

We claim:

The ornamental design for an elastic slipper or similar article, as shown and described.
